ABSTRACT OF THE DISCLOSURE

A flushing valve body contains a main bore within which a piston unit operates. A piston head of this unit divides the main bore into separated upper and lower chambers. A flushing water storage tank communicates with the lower chamber only of the main bore. The piston unit also includes a main valve element which engages the main valve seat of the valve body and a pilot valve is carried by the piston unit and engages a seat thereon. Water enters at the top of the main bore through a restricted passage above the piston unit and pilot valve and a branch inlet passage in the valve body conveys water to said lower chamber directly opposite said storage tank and opposite a portion of the piston unit which lies between the storage tank and the mouth of the branch inlet passage.

The present invention relates to a flush valve for tankless water closets and the like.

In general, bathroom water closets in the home are equipped with tanks for flushing because building codes and custom dictate the use of relatively small diameter water supply pipes leading to plumbing fixtures. In the home, the volume of water from the supply pipe at the fixture and the water pressure may be too low to properly operate pressure-type flush valves and consequently these valves are almost never installed in connection with home water closets.

On the other hand, commercial buildings, including apartments, hotels and office buildings, generally install flush valves upon their water closets because these buildings are constructed with relatively large diameter supply pipes leading to plumbing fixtures and there is always an adequate volume of water under sufficiently high pressure to operate the flush valves.

There is considerable advantage in the use of a flush valve over a flush tank in connection with water closets. The flush tank is bulky and contains a number of rather delicate parts which require frequent maintenance. The tank tends to sweat and is quite slow in filling with considerable noise. The chief objection resides in the rather weak flushing power of the tank which relies on gravity pressure, in contrast to the flush valve which employs full system pressure. These advantages and disadvantages are well known but nevertheless it has been impractical to employ flush valves in the home for the above-stated reasons, including mainly the traditional usage of small diameter supply pipes, such as $\frac{1}{2}$ inch pipes or smaller in contrast to the supply pipes in commercial buildings which are generally a full 1 inch in diameter.

The main objective of the present invention is to provide a flush valve which may be readily installed on water closets in the home and which will operate with complete satisfaction and efficiency in connection with water supply pipes of the size customarily employed in home plumbing.

A further important object is to provide a flush valve which operates in conjunction with a concealed storage tank for water under pressure and which tank discharges its water into the water closet for a complete pressure flush when the valve is opened, in accordance with the operation of the invention. The use of this concealed

2

storage or compression tank renders it possible to utilize the flush valve in connection with a relatively small size water supply pipe. The invention has been found to work satisfactorily with supply pipes down to as small as $\frac{1}{4}$ inch in diameter. It will also work satisfactorily with larger supply pipes up to a full 1 inch diameter pipe, if available.

A further important object of the invention is to provide a flush valve, the use of which will save the home owner as much as 60% on the cost of water pipes while at the same time providing improved flushing without the danger of stoppage and with less noise and inconvenience.

Still another object is to provide a flush valve of the above-mentioned type which employs the minimum number of moving parts and which is highly simplified in construction and operation, rugged and durable, requiring very little maintenance, and which is positive and efficient.

A further object of the invention is to provide a flush valve and concealed compression tank combination which will economize on the use of water while providing a pressure flush up to one gallon per second during operation.

Other objects and advantages of the invention will become apparent during the course of the following detailed description.

In the accompanying drawings forming a part of this application and in which like numerals are employed to designate like parts throughout the same,

FIGURE 1 is a central vertical section through a flush valve embodying the invention, with parts broken away;

FIGURE 2 is a horizontal section taken on line 2—2 of FIGURE 1; and

FIGURE 3 is a similar section taken on line 3—3 of FIGURE 1.

In the drawings, wherein for the purpose of illustration is shown a preferred embodiment of the invention, the numeral 10 designates a flush valve casing having a main cylindrical bore 11. The bore 11 opens through the upper end of the casing 10, which end carries a flange 12 for the mounting of an upper cap 13 rigidly and detachably secured thereto by suitable screw-threaded means 14. A compressible sealing gasket 15 is interposed between the cap 13 and flange 12, as indicated.

The cap 13 has a central screw-threaded opening 16 formed entirely therethrough and the upper portion of this opening receives a screw-threaded water inlet or supply pipe 17. This pipe 17 may be the conventional $\frac{1}{2}$ inch plumbing fixture supply pipe in a home or it may even be a $\frac{1}{4}$ inch pipe or a larger pipe, in some instances. The lower end portion of screw-threaded opening 16 receives a screw-threaded plug 18 therein having a small axial port 19 formed therethrough communicating with a screw driver slot 20 in the bottom of the plug, which in turn communicates directly with an upper chamber 21 of the valve. The upper end of the plug 18 is preferably tapered at 22 to prevent blockage of the small port 19.

The cap 13 is further provided with a lateral branch passage 23 leading from the side of the screw-threaded opening 16 and being of lesser diameter than the opening 16. The branch passage 23 communicates with a vertical branch passage 24 in the valve casing 10, outwardly of the main bore 11, as shown in the drawings, and the lower end of passage 24 leads back into the main bore 11 at 25 and thereby communicates directly with a lower valve chamber 26.

Opposite the passage opening 25, valve casing 10 has an integral screw-threaded extension 27 for connection with the nipple of a storage tank 28 for flushing water under pressure. This is preferably a concealed storage tank which may be about 5 inches in internal diameter

by 5 feet in length, although the shape of the tank may be varied. The storage or compression tank 28 may be concealed in a wall in any convenient manner. The tank could, if desired, be made as an integral chamber on the water closet and connected with the extension or fitting 27 by a pipe. Various arrangements may be used.

The lower end of valve casing 10 carries a depending tubular section 29 of somewhat reduced diameter and having its lower end screw-threaded at 30 for direct connection with the inlet of the water closet bowl. An annular shoulder 31 is formed where the section 29 connects with the main body portion of the valve casing and an annular compressible sealing washer 32 is positioned on the shoulder 31.

A tubular piston body 33 is disposed within the main bore 11 of the casing and has an upper annular flange 34 connected with a compressible washer 35 by means of an upper rigid washer 36 and screws 37. The washer 35 includes radially projecting divergent annular lips 38 which have sealing engagement with the main bore 11 and effectively separate the upper and lower chambers 21 and 26. The flange 34, washer 35 and lips 38 constitute the head of the piston body 33 within the main bore of the valve casing.

Near and above the lower end of piston body 33, the same carries a radial annular flange 39 or valve head adapted to seat upon the washer 32, and this structure constitutes the main valve element of the invention which operates in the manner to be described for pressure flushing the water closet. Below the flange or valve head 39 and at the lower end of piston body 33, the same is provided with a plurality of circumferentially equidistantly spaced radial guide ribs 40 which have relatively close fitting engagement within the bore of tubular section 29 so as to guide the movement of the piston body within the valve casing. Intermediate the ribs 40, the lower end of the tubular piston body is preferably provided with radial discharge openings 41. This is an incidental and optional feature.

A pilot valve element or head 42 of cylindrical construction is adapted to be seated upon the washer 35 and has a downwardly tapering portion 43 to assure proper seating. A long depending stem 44 is carried by the pilot valve element, as shown, and which stem extends entirely through the piston body 33 in spaced relation to its bore. As shown, the lower end of the stem 44 terminates near the bottom of tubular section 29 and well below the bottom of the piston body.

A screw-threaded tubular extension or nipple 45 projects from one side of the section 29 and receives a clamping nut 46 which in turn engages a cap 47 and clamps the same firmly to a guide element 48 which abuts the end of extension 45 and preferably has screw-threaded engagement with the cap, as indicated. A valve operating handle 49 has a flange 50 within the cap 47, engaged by a compressible spring 51 which also engages the guide element 48 and holds the handle in the normal inactive position shown. The handle has a forward stem or rod 52 extending through a seal 53 on the guide element 48 and this rod is adapted to engage the stem 44 and unseat pilot valve element 42 when the handle is actuated by the user against the force of spring 51. Other forms of trip handles or actuators may be employed, if preferred, in place of the arrangement shown in FIGURE 1, which is a preferred arrangement.

The operation of the flush valve is as follows:

When the handle 49 is tripped, the stem 44 is pushed off-center and the pilot valve element 42 is unseated from washer 35 allowing water under pressure in chamber 21 to flow down through tubular piston body 33 and tubular section 29 into the closet bowl. The pressure in chamber 21 is quickly reduced and this allows the entire piston body 33 to rise in main bore 11, thereby unseating main valve element 39 from sealing washer 32. The moment that this occurs, the water under pressure in tank 28 flows

downwardly around the unseated main valve element and through tubular section 29 to the closet bowl where such bowl is pressure flushed effectively with substantially all of the water from the compression tank. As the above action takes place, the rising of the piston body 33 may carry the pilot valve element 42 into contact with the bottom of plug 18.

Gradually, water from the supply pipe 17 passing through the small port 19 fills the upper chamber 21 and creates pressure therein and returns the main valve element 39 to its seat 32 and the pilot valve element 42 is also seated. Even though the pilot valve element 42 may be contacting the bottom of plug 18, water can still enter the upper chamber 21 through the port 19 and communicating screw driver slot 20.

As soon as the main valve element 39 returns to its seat as shown in FIGURE 1, the water flowing through branch passages 23 and 24 and into the chamber 26 will begin to fill the compression tank 28 and will ultimately completely fill this tank with water under pressure in preparation for the next flushing cycle when the handle 49 is again tripped.

The mechanism is extremely simple and can be operated where relatively low water pressure and volume restrictions are encountered. There are only two main moving parts, namely, the piston body 33 and the pilot valve 42, excluding the actuating handle. The valve requires very little maintenance and will function satisfactorily for many years.

In some instances dictated by the location of the water supply pipe, the inlet opening 16 may be located on the side of the valve casing substantially in line with the opening 25 in FIGURE 1. In such case, the plug 18 may be located in the passage 24 with a side opening above the plug leading into the chamber 21. In this case, the cap 13 may be a plain flat cover cap for the valve. The operation remains exactly the same as above-described.

As previously pointed out, the invention may be considered as a compromise between the conventional flush tank arrangement and a pressure flush valve arrangement requiring a large inlet or supply pipe. The present invention retains the major advantages of both systems and also eliminates the major disadvantages of both. That is to say, small size supply pipes can be successfully used without the necessity for the inconvenient and inefficient flush tank and the concealed compression tank enables the valve to perform its intended function efficiently, notwithstanding the rather restricted supply.

It is to be understood that the form of the invention herewith shown and described is to be taken as a preferred example of the same, and that various changes in the shape, size and arrangement of parts may be resorted to, without departing from the spirit of the invention or scope of the subjoined claims.

I claim:

1. A pressure flushing mechanism for commodes and the like comprising an upstanding valve casing having a main substantially vertical bore, an internal shoulder on said casing forming a main valve seat at the lower end of the bore, a flushing water outlet tubular extension on the lower end of the casing below said main seat adapted for connection with a commode to be flushed, a water inlet passage means on the upper end of the casing for delivering water to the mechanism, a branch passage for water formed in said casing and leading from the inlet passage means around one side of the main bore and opening radially and horizontally into the main bore near and above the main seat, a flushing water storage tank for water under pressure connected radially and horizontally into the casing and said main bore substantially diametrically opposite the opening of said branch passage into the main bore, a piston body in the main bore and being movable vertically therein and including an intermediate tubular section of smaller diameter than the main bore interposed directly between the radial opening into said

tank from the main bore and the radial opening from the branch passage into the main bore, whereby water entering the main bore from the branch passage will impinge upon said intermediate tubular section, an upper piston head on said intermediate tubular section having fluid sealing contact with the main bore and dividing the main bore into upper and lower separated chambers, said lower chamber only being in direct communication with said tank and branch passage below said piston head, means forming a pilot valve seat on the top of the piston head surrounding the bore of the intermediate tubular section, the bore of the intermediate tubular section extending through the lower end of the piston body, a main annular valve element on the piston body near and above its lower end engageable with the main seat when the piston body is lowered within the main bore, a pilot valve element loosely mounted upon the piston body including an upper end head engageable with said pilot valve seat and a depending stem extending entirely through the bore of the intermediate tubular section and piston body and below the lower end of the piston body and into said flushing water extension, and a manually operated means on said outlet extension including a part engageable with the pilot valve stem for unseating the pilot valve, there being a restricted water port between said inlet passage means and said upper chamber.

2. A pressure flushing mechanism as defined by claim 1, and guide means on the lower end of said piston body for guiding the piston body within the bore of the outlet tubular extension.

3. A pressure flushing mechanism as defined by claim 1, and wherein said restricted water port is formed within a plug element which projects centrally into the top portion of the upper chamber and said plug element has a recess in its lower end disposed between the restricted port and upper chamber.

5 4. A pressure flushing mechanism as defined by claim 3, and a cap removably mounted on the top of said valve casing and covering the top of the main bore and said upper chamber and containing the water inlet passage means and said plug element having said restricted port and recess.
